UNITED STATES PATENT OFFICE.

CHARLES W. McGARY, OF EVERETT, MASSACHUSETTS, ASSIGNOR OF ONE-HALF TO
HERBERT L. HILDRETH, OF BOSTON, MASSACHUSETTS.

AIR-PUMP.

1,000,615.

Specification of Letters Patent. Patented Aug. 15, 1911.

Application filed January 28, 1910. Serial No. 540,490.

To all whom it may concern:

Be it known that I, CHARLES W. McGARY, a citizen of the United States, residing at Everett, county of Middlesex, State of Massachusetts, have invented a certain new and useful Improvement in Air-Pumps, of which the following is a specification, reference being had therein to the accompanying drawings.

10 My invention relates to air pumps or blowers of the class in which two rotating members or rotors inclosed in a casing coöperate to draw air in through a suction opening and expel it under an increased pressure 15 through a discharge opening. As heretofore constructed, so far as is known to me, blowers of this class have been able to compress the air to a maximum pressure of only eight or ten pounds to the square inch, after which 20 an increase in the speed of the rotors does not increase the amount of compression to any considerable extent. As a result of this fact, it has been necessary to use reciprocating air pumps where the pressure desired 25 was greater than the amount stated. The failure of rotary blowers as heretofore constructed to produce a pressure above eight or ten pounds is believed to have been due to the fact that the pockets of the female rotor 30 operate to carry out of the chamber in which the compressed air is contained a certain amount of the air under pressure, and the proportion which the amount of air carried out by the female rotor bears to the amount 35 carried in by the male rotor increases as the pressure in the discharge outlet increases, so that at a certain speed as much air is carried out by the female rotor as is carried in by the male rotor. Some attempts have 40 been made to cause the compressed air in the pockets of the female rotor to be discharged into the pockets of the male rotor but such attempts have been comparatively ineffectual for the purpose intended, and have 45 greatly lessened the strength of the rotating parts which must be very great to enable the rotors to run at the high speeds required.

My improved rotary air pump is provided 50 with rotors of novel construction which practically eliminate all pocketing of compressed

air and it is found in practice that an air pump embodying my construction will deliver compressed air at a pressure very much in excess of any which it has heretofore been 55 possible to obtain without the use of a reciprocating air pump, so far as is known to me.

The invention will be fully understood from the following description taken in connection with the accompanying drawings, and the novel features are pointed out and clearly defined in the claims at the close of the specification.

In the drawings,—Figure 1 is a vertical 65 section of a device embodying my invention. Figs. 2 to 5 inclusive are sections on line 2—2, Fig. 1, showing the rotors in various successive positions. Fig. 6 also shows a modification intended to give an uneven or 70 jerky suction. Figs. 7 and 8 are details showing the construction of the leakage port by means of which the machine is kept from pounding when running at high speed. Fig. 9 is a vertical section through the casing of 75 a modified form of air pump embodying my invention, the rotors being shown in elevation.

Referring to the drawings,—the casing is shown at 11; the female rotor at 12; and the 80 male rotor at 13. The said casing is constructed in any convenient manner and fits the peripheries and ends of the rotors very closely so as to prevent the escape of air between the proximate surfaces of the casing 85 and rotor. In practice I find it convenient to grind-in the rotors by the use of powdered emery or some other suitable abrading substance. In the form shown in the drawings, the female rotor is supported on an 90 axle 14 and the male rotor on an axle 15, said members being rotated at equal speeds by means of gears 16 and 17, respectively, power being applied to the pulley 18. While I have shown the two rotors as being 95 driven with equal speeds, it will be obvious that they may be driven at different speeds of rotation, if desired for any reason, so long as they are designed to have the same peripheral speeds.

The air to be compressed is drawn in through pipe 19 on the suction side of the

blower and discharged through pipe 20 on the discharge side. The casing on both the suction and discharge sides is made to follow the circumference of the rotors as far as possible, as will be plainly seen from Figs. 2 to 5 inclusive. The casing is shown as ending on the discharge side in a groove 28, which assists in the escape of the compressed air through the discharge pipe.

- 10 The male rotor is constructed with a plurality of longitudinal projections or blades 21, 22 and 23 which are in construction practically gear teeth. In practice I find three to be a convenient number of these blades.
- 15 The body of the male rotor intermediate the adjacent blades is circular, and follows what corresponds to the root circle of the gear. The female rotor 12 is constructed with pockets shaped in cross-section like the 20 space between two adjacent gear teeth of a shape suitable to mesh with the blades of the male rotor. In the drawings, these pockets are numbered 24, 25 and 26, respectively. The space intermediate the 25 walls of the adjacent pockets is solid and follows what may be termed the addendum circle, so that the periphery of the rotor fits closely to the interior of the casing. The pockets in the female rotor are of a depth 30 equal to the length of the blades so that the ends of the blades contact with the bottoms of the pockets and the peripheral portion of the female rotor between two adjacent pockets contacts with the peripheral portion of 35 the male rotor lying between the roots of two adjacent blades. From this it will be seen that there is no end clearance and that the addendum circle of the female rotor contacts with the root circle of the male rotor.
- 40 The blades or teeth and the corresponding walls of the pockets are so constructed as to remain in contact with each other constantly either on the walls or on the bottom of the pocket from the time the blade enters the 45 pocket until it leaves it, so that there is the least possible leakage between the rotors. By this means the compressed air contained in the pocket which is open to the discharge side of the blower is forced back into the 50 discharge side of the blower by the blade which is entering the pocket. As the two rotors are always in contact with each other and the point of contact progresses along the root circle of the male rotor up the side of 55 the blade, along the point of the blade, down the other side of the blade, and again along the root circle toward the next blade, it will be seen that the compressed air is constantly forced backward from the point of 60 contact and no escape, except to the discharge side, is permitted. I find in actual practice that the contact between the male and female members may be made so perfect that no escape of air into the suction side of 65 the air pump is to be observed. I have ac-

complished this by making the blade to correspond in shape with involute gear teeth slightly modified at the point and base to prolong the time of contact until the end of the tooth strikes the bottom of the pocket. It will be understood, of course, that the pockets of the female rotor also carry small quantities of air to the discharge side of the air pump, but the pockets between the blades of the male rotor carry in by far the greater proportion of the air.

It will be seen that when the parts are in the position shown in Fig. 2, the air between the blades 22 and 23 is at substantially atmospheric pressure, and that the air in the space between blades 23 and 21 is at atmospheric pressure, except for any leakage which may have occurred from the discharge side of the air pump. As soon as the blade 21 passes the extreme edge 27 of the casing, the air under pressure from the discharge side rushes into the said space and raises the pressure until it is equal to the pressure on the discharge side. Thereafter the forward movement of the blade 23 compresses all the air in said space and on the discharge side of the air pump until the blade 23 itself passes out of contact with the edge 27 of the casing. If the blades are fitted closely enough to give a maximum efficiency, it is found that pounding results due to the sudden inrush of air under pressure into the space between the two adjacent blades. To prevent this pounding, I form a small leakage port 28, see Figs. 7 and 8, so that the compressed air from the discharge side of the air pump begins to flow slowly into the space between two adjacent blades before the blade reaches the extreme edge of the casing. This construction does away entirely with the undesirable pounding.

The rotors of the blower or air pump embodying my invention may be made solid and compact so that the parts may be run at a very high speed without danger of injury from centrifugal force, but the construction does not prevent the parts being made hollow if desired.

In Fig. 9 I have shown two rotors provided with blades and pockets which are substantially spiral gear teeth. While such construction is somewhat more expensive to produce, it is believed that it would tend to increase materially the quiet operation of the blower as the pressure in the discharge side of the blower is raised less suddenly than in the forms shown in the other figures.

In Fig. 6 there is shown a slight modification of my rotary air pump adapted especially for use in connection with gasoline carbureters in which it is desirable to suck air through a carburetor, thereby causing it to form a mixture with gasoline introduced in the form of a jet and to compress said mixture for use in the cylinders of an

internal combustion engine. Under these conditions it is desirable that the suction on the carburetor be irregular at slow speeds as it is found in practice that a steady current 5 of air moving with less than a certain velocity will not break up the jet of gasoline and form the desired mixture. It is, therefore, desirable that the suction be irregular or jerky, as thereby the formation of the mixture 10 at slow speeds is greatly improved. To accomplish this result, I place the suction opening 35 part way down the casing of the male rotor and make such suction opening in the form of a narrow port which is closed at times by the end of the blade of the male rotor. When the parts are in the position shown in Fig. 6, the further movement of the blade 21 of the male rotor forms a partial vacuum in the space back of said blade, 15 said vacuum becoming more perfect as the said blade approaches the port 35. As soon as the blade passes the port, the gasoline mixture rushes in suddenly to fill the vacuum. In this form, a little clearance is 20 made between the female rotor and the casing at about the point 36 to enable the pocket 24 to be filled with air, when the part 35 is uncovered by the tooth, as otherwise the pocket 24 would tend to carry a partial 25 vacuum forward and lessen the efficiency. It will be found that at slow speeds the suction through the port 35 is very jerky, thereby inducing more perfect carburetion 30 at slow speeds. At high speeds, little or no 35 difference will be seen in the action over that of the form shown in the other figures.

What I claim is:

1. In a rotary air pump, the combination of a female rotor and a male rotor, said female rotor being provided with a series of peripheral pockets and said male rotor being provided with a corresponding series of blades equal in number with the pockets of the female rotor, the distances between 40 the pockets of the female rotor being greater than the width of the pockets and the distances between the teeth of the male rotor being greater than the width of the teeth, the spaces between the pockets of the female 45 rotor being solid and the spaces between the teeth of the male rotor being hollow, the radius of sweep of the teeth of the male rotor being the same as the radius of sweep of the body of the female rotor, said two 50 rotors having their axes of rotation parallel with each other and spaced apart so that the teeth of the male rotor will mesh with and bottom in the pockets of the female 55 rotor during the rotation and the peripheries of the bodies of the two rotors will have a sliding contact with each other and a casing having two intersecting cylindrical 60 chambers parallel with each other and opening into each other at their intersecting portions, the interior diameter of both chambers being equal to each other and to the diameter of the circle swept by said rotors 65 whereby there is a close sliding fit of the rotors within said cylindrical chambers and permitting rotation of the rotors, said casing having an inlet opening and a discharge opening, said rotors being at all times in contact with each other at some point between the inlet and the discharge openings. 70
2. In a rotary air pump, the combination of a female rotor and a male rotor, said female rotor being provided with a series of peripheral pockets and said male rotor being provided with a corresponding series of blades equal in number with the pockets of the female rotor, the distances between the teeth of the male rotor being greater than the width of the teeth, the spaces between the pockets of the female 75 rotor being solid and the spaces between the teeth of the male rotor being hollow, the radius of sweep of the teeth of the male rotor being the same as the radius of sweep of the body of the female rotor, said two rotors having their axes of rotation parallel with each other and spaced apart so that the teeth of the male rotor will mesh with and bottom in the pockets of the female 80 rotor during the rotation and the peripheries of the bodies of the two rotors will have a sliding contact with each other and a casing having two intersecting cylindrical 85 chambers parallel with each other and opening into each other at their intersecting portions, the interior diameter of both chambers being equal to each other and to the diameter of the circle swept by said rotors 90 whereby there is a close sliding fit of the rotors within said cylindrical chambers and permitting rotation of the rotors, said casing having an inlet opening and a discharge opening, said rotors being at all times in contact with each other at some point between the inlet and the discharge openings. 95
3. In a rotary air pump, the combination of a female rotor and a male rotor, said female rotor being provided with a series of peripheral pockets and said male rotor being provided with a corresponding series of blades equal in number with the pockets of the female rotor, the distances between the pockets of the female rotor being greater than the width of the pockets and the distances between the teeth of the male rotor being greater than the width of the teeth, the spaces between the pockets of the female 100 rotor being solid and the spaces between the teeth of the male rotor being hollow, the radius of sweep of the teeth of the male rotor being the same as the radius of sweep of the body of the female rotor, said two rotors having their axes of rotation parallel with each other and spaced apart so that the teeth of the male rotor will mesh with and bottom in the pockets of the female 105 rotor during the rotation and the peripheries of the bodies of the two rotors will have a sliding contact with each other and a casing having two intersecting cylindrical 110 chambers parallel with each other and opening into each other at their intersecting portions, the interior diameter of both chambers being equal to each other and to the diameter of the circle swept by said rotors 115 whereby there is a close sliding fit of the rotors within said cylindrical chambers and permitting rotation of the rotors, said casing having an inlet opening and a discharge opening, said rotors being at all times in contact with each other at some point between the inlet and the discharge openings. 120
4. In a rotary air pump, the combination of a female rotor and a male rotor, said female rotor being provided with a series of peripheral pockets and said male rotor being provided with a corresponding series of blades equal in number with the pockets of the female rotor, the distances between the pockets of the female rotor being greater than the width of the pockets and the distances between the teeth of the male rotor being greater than the width of the teeth, the spaces between the pockets of the female 125 rotor being solid and the spaces between the teeth of the male rotor being hollow, the radius of sweep of the teeth of the male rotor being the same as the radius of sweep of the body of the female rotor, said two rotors having their axes of rotation parallel with each other and spaced apart so that the teeth of the male rotor will mesh with and bottom in the pockets of the female rotor during the rotation and the peripheries of the bodies of the two rotors will have a sliding contact with each other and a casing having two intersecting cylindrical 130 chambers parallel with each other and opening into each other at their intersecting portions, the interior diameter of both chambers being equal to each other and to the diameter of the circle swept by said rotors whereby there is a close sliding fit of the rotors within said cylindrical chambers and permitting rotation of the rotors, said casing having an inlet opening and a discharge opening, said rotors being at all times in contact with each other at some point between the inlet and the discharge openings. 135

other and a casing having two intersecting cylindrical chambers parallel with each other and opening into each other at their intersecting portions, the interior diameter of both chambers being equal to each other and to the diameter of the circle swept by said rotors whereby there is a close sliding fit of the rotors within said cylindrical

chambers and permitting rotation of the rotors.

In testimony whereof I affix my signature, in presence of two witnesses.

CHARLES W. McGARY.
